PAPER OPTICAL ILLUSION TOY

Carey Claude Cloud, Morgantown, Ind.

Application December 8, 1949, Serial No. 131,778

3 Claims. (Cl. 88—16)

1

My invention relates to an optical illusion toy which is made entirely of paper. It is among the objects of my invention to provide a toy which can be made in an extremely economical manner through the use of no material other than paper and ink. There are many commercial products on the market, particularly candies and confections for sale to children, which include in their packages a small toy or novelty. This novelty is extremely important in the sale of the products because it is hidden inside the package and serves to intrigue the child into buying the product in order to obtain the novelty.

Due to the high cost of manufacturing, any toy or novelty which is at all complicated or which requires any amount of assembly work in its construction, cannot be used for this purpose.

It is among the objections of my invention to provide a toy or novelty which is particularly designed for this type of use. My toy is constructed entirely of paper or cardboard, which is printed and die cut. A large number of them can be printed and die cut from one large sheet and then separated. No metal, plastic or assembly work is required.

It is a further object of my invention to provide such a paper toy or novelty which is unusual and which will amuse and fascinate a child or an adult. This is accomplished by providing a toy which comprises a piece of paper with an image on each side. Through the use of the paper itself, the child can cause the paper to be rotated rapidly, so that both sides of the paper pass before his eyes in rapid succession.

It is well known that the human eye retains an image for a period beyond the time when the object is actually present before the eye. For that reason, the effect of the rapid rotation of my toy is to cause the images on the two sides of the paper to appear to be superimposed upon each other. Using this principle, there is an endless variety of objects which may be portrayed for humorous or startling effects.

A further object of my invention is to provide such a toy in which rapid rotation may be achieved for obtaining the maximum optical effect, without providing any externally supplied means of rotation.

My invention also comprises such other objects, advantages and capabilities as will later more fully appear and which are inherently possessed by my invention.

While I have shown in the accompanying drawings a preferred embodiment of my invention, yet it is to be understood that the same is sus-

2

ceptible of modification and change without departing from the spirit of my invention.

Referring to the drawings, Fig. 1 is a front view of one side of my paper optical toy blank; Fig. 2 is a front view of the opposite side of my blank; Fig. 3 is a front view of my blank showing the corners removed; Fig. 4 is a front view of my blank showing the end portions twisted to form strings; Fig. 5 is a top plan view of my blank with the end portions twisted to form strings and Fig. 6 is a front view of my toy in use, showing the positioning of the hands and the optical illusion effect which is achieved through operation of my toy.

A preferred embodiment of my invention comprises a substantially flat rectangular blank 10, which is preferably formed of a tough, long-fibered paper stock for strength. Other type of paper, cardboard or other material may be used. Blank 10 is provided at each of its four corners with right angle die cuts 11, 12, 13 and 14. Each of these cuts is substantially square in shape and is rounded at its right angle turn.

The cutting rules which make the four corner cuts 11, 12, 13 and 14 are nicked to make a dull spot so that the corners are not cut entirely free from the blank 10.

The portions of blank 10 which are outlined by cuts 11, 12, 13 and 14 comprise almost all of the ends of blank 10, leaving only narrow end portions 15 and 16 of the blank between them. A pair of straight line cuts 17 and 18 extends longitudinally along blank 10 to bisect the end portions 15 and 16.

On the remaining portions of blank 10 is imprinted a pair of pictures 19 and 20, one on each side of blank 10. It has been found that a white figure superimposed on a black background is best for obtaining the desired optical effect. Pictures 19 and 20 are so positioned and designed that they will create a humorous, unusual or startling effect when superimposed.

Among the pictures which illustrate this effect are those of a cowboy and horse, a dog and cat, a cat and mouse, and a bull and bull fighter. These are only a few of the many possible subjects which may be used.

In order to facilitate the use of my toy, instructions are imprinted in the corners which are outlined by cuts 11, 12, 13 and 14. The first instruction is preferably contained in the upper left hand corner of my blank 10. It reads "(1) Break off these four corner pieces."

The next instruction is contained in the lower left hand corner of my blank 10 and reads "(2)

Next—Twist both ends into strings." The third instruction is contained in the upper right hand corner of my blank 10 and reads "(3) Hold (see below), then twirl rapidly." In the lower right hand corner of my blank 10 is an illustration showing the toy in use, with the hands of the user illustrated in their proper position. It is contemplated that these instructions may be printed on both sides of my blank 10 or on only one side, or omitted entirely.

In use, my toy as found by the child comprises the rectangular blank 10, which is die cut and printed in the manner described above. Following the first instruction, the child breaks off the four corner pieces. This is accomplished by tearing them along the lines of cuts 11, 12, 13 and 14. When this has been done, there remains of the blank 10 only the picture portion and the two narrow end pieces 15 and 16, which extend outwardly from blank 10 at each end thereof.

Following the next instruction, the child twists both end portions 15 and 16 into strings. This may be accomplished by merely twisting them some 5 or 10 times. Cuts 17 and 18 serve to separate the end portions 15 and 16 into two members, which may be twisted around each other in order to simulate a string.

Following the third instruction, the child then holds the strings between the thumb and index finger of each hand and twirls the blank 10 rapidly. The correct manner of holding and twirling my toy is illustrated in the fourth instruction. When my toy is held before the eyes and operated in this manner, pictures 19 and 20 appear to be superimposed on each other.

In making my toy, it should be understood that a plurality of my rectangular blanks 10 may be printed and die cut from a single sheet of paper or similar material. This may be accomplished by using formed cutting rules to separate them from each other.

Having thus described my invention, I claim:

1. An optical illusion toy comprising a substantially flat rectangular paper blank, said blank having four corner die cuts, each of said corner cuts having a longitudinal portion and a transverse portion to outline a substantially square corner of said blank, said blank having a pair of integral end portions positioned between the longitudinal portions of said corner cuts, a pair of straight line cuts bisecting said end portions, said blank having a pair of pictures imprinted on the opposite sides thereof, said blank having instructions for operation of said toy imprinted in the four corners outlined by said corner cuts, said corner cuts adapted to permit the removal of the four corners from said blank to leave said end portions projecting therefrom, said end portions adapted to be twisted to form strings, said straight line cuts adapted to facilitate the formation of said end portions into strings, said strings adapted to be held between the thumb and index finger of each hand, said strings when twirled between said thumbs and

index fingers adapted to cause said blank to be rotated rapidly so as to cause said pictures on the opposite sides of said blank to appear to be superimposed on each other to form a single optical impression.

2. An optical illusion toy comprising a substantially flat blank formed of paper, said blank having four corner cuts, each of said corner cuts having a longitudinal portion and a transverse portion to outline a corner of said blank, said blank having a pair of integral end portions positioned between the longitudinal portions of said corner cuts, a pair of straight line cuts extending longitudinally along said end portions, said blank having a pair of pictures on opposite sides thereof, said corner cuts adapted to permit the removal of the corners from said blank to leave said end portions projecting therefrom, said straight line cuts adapted to facilitate the twisting of said end portions to form strings, said strings adapted to be held between the thumb and index finger of each hand, said strings when twirled between said thumbs and index fingers adapted to cause said blank to be rotated rapidly so as to cause said pictures on the opposite sides of said blank to appear to be superimposed on each other to form a single optical impression.

3. An optical illusion toy comprising a substantially flat blank formed of paper, said blank having four corner cuts, each of said corner cuts having a longitudinal portion and a transverse portion to outline a corner of said blank, said blank having a pair of integral end portions positioned between the longitudinal portions of said corner cuts, said blank having a pair of pictures on opposite sides thereof, said corner cuts adapted to permit the removal of the corners from said blank to leave said end portions projecting therefrom, said end portions adapted to be twisted to form strings, said strings adapted to be held between the thumb and index finger of each hand, said strings when twirled between said thumbs and index fingers adapted to cause said blank to be rotated rapidly so as to cause said pictures on the opposite sides of said blank to appear to be superimposed on each other to form a single optical impression.
